A. Crowley

UNITED STATES PATENT OFFICE

CLIFFORD S. WINSOR, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK

CLEANER FOR SANDING MACHINES

Application filed July 26, 1927. Serial No. 208,450.

This invention relates to sanding machines and more particularly to means for removing dust and other particles from the sanding element.

5 Heretofore machines of the above category have been constructed with a suction device to draw all the substances that may have accumulated on the sander during the operation of the machine. It has been found that 10 with a device of this character that all the accumulated particles are not withdrawn by the suction, but have a tendency to follow the sander resulting in particles of dust continually floating about the room accumulating not 15 only on the machine and in the room but also on the operator. Obviously when a machine of this type is in operation throughout the day, an operator has to work under very unhealthy conditions.

20 According to my invention I have succeeded in constructing a sanding machine wherein all particles of dust or other substances on the sander are removed, resulting in healthful conditions in the room in which 25 the machine is located. Also in addition to removing the dust particles from the sander, the life of the sander is materially lengthened due to the fact that the sander is prevented from becoming glazed or clogged with the 30 dust accumulated thereon.

An object of my invention is to provide a new and improved type of sanding machine wherein all substances accumulated on the sander are removed during the operation of 35 the machine.

Another object of the invention is to materially lengthen the life of the sander by preventing it from becoming glazed or clogged.

40 These and other objects of my invention will be hereinafter pointed out in the accompanying specification and claims and shown in the drawing which shows by way of illustration what I claim to be a preferred embodiment of my invention.

In the accompanying drawing I have shown for the purpose of illustration one form of mechanism embodying the invention in which a front elevational view of my sanding device is shown.

The preferred form of my invention consists of a sander belt mounted on suitable rollers rotated by means of a motor. During the operation of the machine, the belt in passing a predetermined point will be acted upon by 55 a blast of air which will loosen all dust particles which may have accumulated on the belt; a suction device in turn removing the loosened particles from the machine.

Reference will now be had to the drawing 60 wherein the construction of my device is illustrated. The sander belt 10 is mounted upon a plurality of rollers 11 and 11', the roller 11' being rotatably mounted on an arm 12. The arm 12 as will be noted is pivoted at 13 and carries at its opposite end a weight 14 which at all times keeps a yielding tension on the sander belt 10 so that an operator may easily 65 press the sander belt against the board 15 during the operation of the machine. A motor (not shown) of suitable power is connected to the shaft 16 upon which one of the rollers 11 is rigidly mounted. A main pipe 17 having a laterally extending pipe 18 connected thereto by an elbow 19 projects beneath the sander belt as viewed in the figure. Connected at 20 to the main pipe 17 through 70 suitable elbows, is another laterally extending pipe 21. Each of the pipes 18 and 21 has a plurality of holes 22 therein through which 75 compressed air is forced against the sander belt 10. Suitable shields 23 and 23' enclose this section of the belt, there being sufficient clearance between the shields so that the belt may pass between them. The shield 23' has 80 associated therewith a pipe 24 which is connected at its opposite end to a suction device 85 (not shown).

When the machine is to be operated, a valve 20a on the main pipe 17 is opened thereby allowing compressed air from a tank in some part of the building to escape through the openings 22 in the pipes 18 and 21. A motor connected to the shaft 16 is then started causing the belt 10 to function. It is, of course, to be understood that the suction device connected to the end of the pipe 24 is also started. The operator with a suitable hand tool presses the belt 10 against the board 15 moving the board during the sanding operation. As the 90 95 100

belt passes the pipes 18 and 21 compressed air escaping through the holes 22 in the pipes will loosen any particles of dust which may have accumulated on the belt during the sanding operation. Preferably the holes 22 are so located that the compressed air is forced diagonally against the belt toward the discharge pipe 24. Thus all the dust loosened is sucked from the belt through the discharge pipe 24 by means of a suction device. Obviously with a construction of this kind a sanitary condition will prevail at all times.

During the operation of the machine dust that is created at the working point tends to be drawn by the current of air created by the speed of the belt toward the blowing device when, aided by the operation of the blower, it is sucked into the shields 23 and 23' and carried from the machine through the pipe 24.

While I have shown and described and pointed out the fundamental novel features of the invention as applied to a single modification it will be understood that various omissions and substitutions and changes in the form and details of the device illustrated and in its operation may be made by those skilled in the art without departing from the spirit of the invention. I intend to be limited therefore only as indicated by the scope of the following claims.

I claim:

1. A device comprising in combination a sanding belt, a supporting pulley therefor, a casing surrounding substantially the entire periphery and side of said pulley and having openings for permitting passage of the belt therethrough, one side of said casing being provided with a suction device for conducting dust and loose particles away from the belt, and a plurality of blowers separate from the suction device and at diametrically opposite sides of the casing and adjacent the said opening for directing air against the belt to loosen the particles thereon for removal by said suction device.

2. In combination with a sanding belt and a supporting pulley therefor, a casing enclosing both sides of said pulley and having openings for permitting passage of said belt through the casing, one side of said casing being provided with a suction flue, and a blower positioned within said casing and mounted independently thereof for blowing loose particles from the belt surface to be removed by said suction device.

3. In combination, a sanding belt, a supporting pulley therefor, a substantially circular casing enclosing substantially the whole circumference of said pulley, said casing having a suction flue for removing particles from the belt and dust from the casing, a pair of blowers positioned within said casing and on opposite sides of said flue for blowing loose particles and dust from the belt and

casing for removal by said suction flue a single air supply pipe to which both blowers are connected, and a valve on said pipe accessibly close to the said casing for controlling the air supply to the blowers.

In testimony whereof I hereto affix my signature.

CLIFFORD S. WINSOR.
